US00D444112S

(12) United States Design Patent **(10) Patent No.:** **US D444,112 S**
Shimazu **(45) Date of Patent:** **** Jun. 26, 2001**

(54) BUMPER HAVING A RADIATOR GRILL PORTION

896204 1/1994 (JP).
896282 1/1994 (JP).

(75) Inventor: **Yutaka Shimazu**, Aki-gun (JP)

* cited by examiner

(73) Assignee: **Mazda Motor Corporation**,
Hiroshima-ken (JP)

Primary Examiner—Melody N. Brown
(74) Attorney, Agent, or Firm:—Sidley & Austin; Hugh A. Abrams

(**) Term: **14 Years**

(57) CLAIM

(21) Appl. No.: **29/102,786**

The ornamental design for a bumper having a radiator grill portion, as shown and described.

(22) Filed: **Mar. 31, 1999**

DESCRIPTION

(51) LOC (7) Cl. **12-16**
(52) U.S. Cl. **D12/169**
(58) Field of Search **D12/163, 169,
D12/90-92; 180/68.6, 69.21, 68.1; 293/115,
102**
